REFRIGERATOR PARTITION STRUCTURE

Enoch Swedman, St. Paul, Minn., assignor to
Seeger Refrigerator Company, a corporation of
Minnesota

Application January 9, 1946, Serial No. 639,960

8 Claims. (Cl. 220—22)

1

My invention relates to an improvement in refrigerator partition structure wherein it is desired to provide a simple and effective series of partition forming elements by means of which the interior of a freezing cabinet may be divided.

In the manufacture of freezing units used for the storage of frozen foods and the like some difficulty is experienced in storing various types of foods so that they may be readily located. This is particularly true in the well type of cabinet which is often filled with small packages of frozen food products or the like. It sometimes occurs that the particular package desired is near the bottom of the cabinet, making it usually necessary to remove much of the contents of the cabinet before locating the particular product desired. In inserting products into the refrigerator and in removing them from time to time to gain access to other frozen products stored in the lower portion of the cabinet the various packages often get mixed up and misplaced, making it extremely difficult to find any particular package.

It is an object of the present invention to provide a partition structure which is adjustable in size and in position within the refrigerator cabinet body. As a result storage wells of various sizes and shapes may be formed to accommodate packages of different sizes. Furthermore, products of similar nature may be maintained in one definite portion of the refrigerator body, making all of the contents of the refrigerator easy to find when necessary.

A further feature of the present invention resides in providing an adjustable partition forming structure for the lower portion of the cabinet body and in providing removable and slidably supported baskets for containing other products in the upper portion of the cabinet body. As a result any of the products within the refrigerator may be quickly found and quickly removed without the necessity of removing much of the contents of the body.

A further feature of the present invention resides in the provision of an adjustable partition structure for use in the lower portion of a refrigerator cabinet body and in the provision of a plurality of baskets supported in the upper portion of the cabinet body. These baskets are slidably supported so that they may be moved from one position to another. The baskets are of such a size as to not entirely fill the upper portion of the refrigerator, making it possible to slide the baskets in either direction to gain access to frozen products stored in any part of the lower portion of the refrigerator.

A feature of the present invention lies in the

2

provision of a partition wall removably supported on the floor of the refrigerator compartment and a second partition member which may be removably fastened to the first partition to extend at right angles thereto. As a result a T-shaped partition member is formed which may divide one end of the lower portion of the refrigerator into two compartments which are adjustable in size.

10 A feature of the present invention resides in the manner of supporting the baskets in the refrigerator. The baskets are provided with laterally extending flanges which extend over and rest upon the top gaskets of the refrigerator cabinet. In actual practice it has been found that this gasket usually becomes frosted to some extent and presents a rather slippery sliding surface on which the baskets and trays may be supported.

These and other objects and novel features of the invention will be more clearly and fully set forth in the following specification and claims.

In the drawings forming a part of the specification:

25 Figure 1 is a perspective view of a refrigerator of the well type, a portion of which has been broken away to show the partition structure therein.

Figure 2 is a perspective view of one of the baskets supported within the refrigerator body.

30 Figure 3 is a perspective view of one of the partition forming members used in the lower portion of the refrigerator body.

Figure 4 is a perspective view of a second partition forming member for the lower portion of the refrigerator body.

Figure 5 is a perspective view of a tray which is supported at the top of the refrigerator body.

Figure 6 is a perspective view of a rubber bumper which is mounted upon the partition forming members to hold the members in place and to prevent injury to the lining of the cabinet.

40 The refrigerator cabinet A, illustrated in Figure 1 of the drawings is typical of a well type freezer for which the partition forming members are most suited. The refrigerator cabinet A includes an insulated bottom wall 10, insulated end walls 11 and 12, an insulated rear wall 13, and an insulated front wall not illustrated in the drawings. The walls 11, 12 and 13, together with the front wall form an open topped cabinet of the well type, which has been found extremely efficient and effective for freezing purposes. In the particular cabinet illustrated the compartment 14 is provided for the compressor and mechanical apparatus necessary to refrigerate

55

the cabinet. The compartment 14 in the structure illustrated is uninsulated and is formed by extending the wall 15 upwardly from the bottom wall 10 at a point spaced from the end wall 12, and in providing an insulated elevated bottom wall 16 connecting the wall 15 to the wall 12.

As is usual with such structures the cabinet body preferably includes a metallic outer covering member 7 and a metallic inner liner 19. Insulation material 20 is provided between the inner and outer walls. A non-metallic breaker strip 21 of rubber or other suitable material connects the inner and outer walls so as to restrict the passage of heat into the refrigerator body.

A cover 22 is hinged at 23 to the rear cabinet wall 13. The cover 22 is usually provided with an outer metallic covering 24, an inner metallic covering 25, and insulation 26 between these coverings. A gasket strip 27 forms a breaker strip between the inner and outer coverings to restrict the passage of heat into the cabinet.

Because of the depth of the refrigerator cabinet A, difficulty might sometimes be experienced in locating a package placed near the bottom of the cabinet unless the position of the package was definitely known. In many such cabinets, it is common practice to merely lay wrapped packages one upon the other in the cabinet making it necessary to remove all of the uppermost packages, or many of the same in order to gain access to certain of the packages at the bottom of the cabinet. It is this difficulty which the present invention is designed to eliminate.

With reference now to Figure 4 of the drawings, it will be noted that a partition element B is provided which is of proper length to fit between the front and rear walls of the refrigerator to form a partition between the ends of the cabinet. The partition member B includes an inverted substantially U-shaped frame 29 which includes an upper transverse member 30 and a pair of substantially parallel uprights 31 and 32. A pair of generally parallel feet 33 are secured to the lower extremity of the vertical supports 31 and 32 so as to hold the frame 29 in an upright position. The lower ends of the uprights 31 and 32 diverge to some extent at 34 and 35, respectively, so that the feet 33 may be positioned in close contact with the front and rear cabinet walls, while the major portion of the uprights 31 and 32 may be spaced slightly therefrom.

A series of transversely extending rods or wires 36 connect the uprights 31 and 32 to stiffen the structure and also assist in forming a partition wall. The wires or rods 36 are spot welded or otherwise terminally affixed to the uprights 31 and 32. A series of substantially parallel vertical rods or wires 37 are connected between the transverse member 30 of the frame 29 and the lowermost transverse rod 36. The vertical rods or wires 37 are spot welded or otherwise affixed in place and may be spot welded to the intersecting rods 36 to form a firm structure. It will be seen that the partition member B thus provides a wall for retaining packages or boxes in a certain area of the cabinet without forming any appreciable bar to the free circulation of air through the cabinet.

Near the top of each of the uprights 31 and 32 is provided a rubber bumper C. This bumper is formed as best illustrated in Figure 6 of the drawings and comprises merely a substantially rectangular block 39 of rubber or other suitable resilient material having an opening 40 or aperture extending therethrough. The body 39 is slit

5 at 41 from one edge of the body to the aperture 40 so that the slit side of the bumper may be spread apart to allow the bumper to be attached to the uprights. The upright fits snugly within the aperture 40 when the bumper is in place.

In Figure 3 of the drawings is disclosed a partition forming element D which is used in combination with the partition forming element B. In preferred form the partition D comprises an inverted substantially U-shaped frame 42 comprising a transverse top member 43 and a pair of substantially parallel upright frame sides 44 and 45. In the construction illustrated the arm 44 is somewhat longer than the upright 45 as the upright 44 is designed to extend down into engagement with the front of the compartment while the upright side 45 terminates in spaced relation to the front.

20 A series of rods or wires 46 extend between the upright sides 44 and 45 and are terminally connected thereto by spot welding or any other suitable means. A series of vertically extending rods or wires 47 extend from the transverse member 43 to the lowermost rod 46 and are spot welded or otherwise affixed terminally to these elements. Thus a grid structure is formed of crossed rods or wires which are supported by the frame 42 and which may be spot welded at their intersections if desired.

25 30 A pair of attaching clips 49 are provided on the upright 45. These clips 49 include a substantially flat plate-like body having a pair of hook shaped tongues 50 extending in spaced relation from the upper edge thereof. These hook shaped tongues 35 50 are designed to hook over certain of the transverse rods 36 of the partition B to hold the partition D at right angles to the partition B. The spacing of the tongues 50 permits the hooks to engage opposite sides of one of the upright rods 40 37 of the partition B. As a result the partition D may be securely attached to the partition B by merely hooking the attaching clips 49 of the partition D onto the rods 36 of the partition B.

45 It will be noted that when the partitions B and D are attached they form a T-shaped partition structure which is capable of dividing either end of the refrigerator cabinet into two separate compartments. The relative size of the two compartments may be readily adjusted by changing the position of the partition D or the partition B. In 50 preferred form the cabinet A is provided with two of the partitions B and two or more of the partitions D so that both ends of the cabinet may be divided into the requisite number of separate compartments. With such an arrangement a space is provided between the two partitions B, which in itself forms an additional compartment.

55 The baskets E for supporting food products and the like in the upper portion of the cabinet body are preferably constructed as best illustrated in Figure 2 of the drawings. The baskets E include a top frame 51 which is of rectangular shape as viewed from above, but which includes ends which are substantially above the plane of the sides. The frame 51 includes a pair of substantially parallel sides 52 which terminate in upwardly extending off-sets 53 and 54 respectively. The vertical off-sets 53 and 54 are connected by end connecting members 55.

60 65 A series of substantially parallel U-shaped rods 56 form the ends of the basket E. These U-shaped rods 56 each include an end upright 57, a transverse bottom member 59, and a second vertical upright 60 parallel to the upright 57. Each of the uprights terminate in an out-

wardly extending end. Each upright 57 is provided with an outwardly extending end 61, while each upright 60 terminates in an outwardly extending end 62. The ends 61 are connected together and to the end 55 of the frame 51 by means of a U-shaped rod 63. The U-shaped rod 63 is terminally connected to the end 55 of the frame 51 and is connected at spaced points throughout its length to the spaced ends 61 of the U-shaped basket body forming members 56.

The ends 62 of the upright 60 are likewise connected to each other and to the end 55 of the frame 51 by the U-shaped rod 64. This rod 64 is terminally connected to the end frame member 55 and is connected at spaced points throughout its length to the various ends 62 of the basket body forming members 56. As a result the basket is provided with a frame 51 of a size to fit within the breaker strip 21 of the cabinet A, while the ends of the body forming members 56 form outwardly extending flanges which are designed to rest upon the surface of the breaker strip 21.

The basket E is provided with a series of U-shaped strips 65 which cross the U-shaped members 56 at right angles. The rods 65 each include substantially parallel vertical sides 66 and 67 which are connected at their lower extremity by transverse bottom forming members 69. Thus the basket body includes a series of U-shaped members extending from opposite sides and opposite ends of the frame 51 and which cross at right angles to form the bottom of the basket.

The sides of the basket are reinforced by rectangular frame elements 70 which are connected to the U-shaped members 65 and 56 at spaced elevations. Thus all of the walls of the basket comprise crossed rods which permit a free circulation of air and at the same time properly hold the products desired.

In Figures 1 and 5 of the drawings is disclosed a tray F which may be used in conjunction with the basket E. The tray F includes a rectangular bottom panel 71 having side walls 72 and an encircling flange 73. The bottom panel 72 may include stiffening ribs 74 if desired. The walls 72 are of proper dimension to fit within the breaker strip 21 at the top of the cabinet A. Thus when the tray is in place the end portions 75 and 76 of the flange 73 rest upon the upper surface of the breaker strip 21 and are supported thereby. Spaced off-sets 77 may be provided in the flanges 75 and 76 if desired to hold the major portion of the flanges spaced above the breaker strip. Thus the tray F may be readily slid along the top of the refrigerator into any desired position. The tray may serve to hold certain products contained within the refrigerator. This tray, however, is of particular value in supporting packages removed from any of the refrigerator compartments, either to be removed from the refrigerator or to be replaced therein. Thus if one of the compartments is used to hold frozen vegetables of two or three different types, the packages may be placed upon the tray F temporarily until the desired type of vegetable is located. The packages on the tray may then be returned to their proper position in the refrigerator. Similarly the tray F may be used to support packages to be removed from the refrigerator and may provide a convenient carrying tray for these packages.

The operation of the partition forming struc-

ture is believed obvious from the foregoing description. The partitions B and D may be assembled to provide compartments of any desired relative size at either end of the cabinet.

5 In Figure 1 the two partitions B and two partitions D are used to divide the bottom of the compartment into five separate compartments. The baskets E support other products above the level of the partitions and these baskets are of less width than the bottom of the compartment so that they may be moved to one end or to the other to gain access to any portion of the contents of the cabinet. Flanges on the baskets E and on the tray F rest upon the breaker strip 21 which is of non-metallic material. This breaker strip has a tendency to frost to some extent due to its position and due to the fact that it extends out of the refrigerated area. It has the advantage therefore that the upper surface of the breaker strip forms a slippery surface over which the flanges of the tray and baskets may slide.

10 In accordance with the patent statutes, I have described the principles of construction and operation of my refrigerator partition structure, and while I have endeavored to set forth the best embodiment thereof, I desire to have it understood that obvious changes may be made within the scope of the following claims without departing from the spirit of my invention.

15 I claim:

1. A partition forming structure for a refrigerator cabinet having a bottom panel and encircling rectangularly arranged walls, the structure comprising an upright foraminous wall 20 slidably supported on the cabinet bottom panel, wall supporting feet engageable with opposed cabinet walls at the base of said foraminous wall 25 slidably supported on the cabinet bottom panel extending at substantially right angles to the plane of the foraminous wall, and rubber bumper means secured to the edges of said foraminous wall to space the same from the refrigerator cabinet walls.

2. A partition structure for a refrigerator compartment comprising an inverted substantially U-shaped frame, feet extending from the lower end of said frame to support the same in upright position, a series of transversely extending rods connecting opposite sides of said frame, a series 30 of vertically extending rods connecting the top of said frame and said transversely extending rods, and rubber bumper means secured to opposite sides of said frame near the top thereof.

3. A compartment structure for a refrigerator including a pair of partition forming elements, the first of said elements comprising a wall including a frame, a pair of transversely extending feet on said frame to support the frame in an upright position, wire rod means extending between opposite ends of said frame, the second of 40 said partition forming elements comprising a frame having a foot on one end thereof and hook means on the other end thereof, said hook means being designed for engagement with the transversely extending wire rod means of the first frame.

4. A compartment structure for a refrigerator including a pair of partition walls, the first of said walls comprising a frame and a means thereon to support the frame in an upright position, transversely extending rods extending in parallel relation between opposite ends of said frame, the second partition wall including a frame having a 45 foot on one end thereof and a pair of hooks on

the other end thereof, said hooks being designed to engage said parallel rods of said first partition wall.

5. A compartment structure for a refrigerator including a first partition wall including a frame means supporting said frame in an upright position, horizontally extending wire rod means extending between the ends of said frame, and vertically extending rod means in said frame intersecting said first named rod means, the second partition wall including a second frame, a foot on one end of said second frame, and bifurcated hook means on the other end of said second frame designed to adjustably and removably engage said rod means, said bifurcated hook means being designed to engage said horizontally extending rod means and to straddle one of said vertically extending rod means.

6. A compartment forming structure for a refrigerator including a partition wall, means for holding said partition wall in a vertical position, said partition wall including a frame, a pair of horizontally extending wire rods extending between opposite ends of said frame, a series of vertically extending wire rods intersecting said first named wire rods, a second partition wall including a second frame, a foot at one end of said second frame, and a pair of bifurcated hooks on the other end of said second frame, said bifurcated hooks being designed to adjustably engage said horizontally extending wire rods and to straddle a vertically extending wire rod.

7. A compartment forming structure for a refrigerator having a bottom panel and angularly arranged encircling wall panels secured marginally thereto, two of the wall panels being opposed and parallel, the structure including a partition wall of a length to fit between said parallel walls, right angularly extending feet at each end of said partition wall and designed to slidably support the partition wall upon the bottom panel of the refrigerator near the junctures thereof with said parallel wall panels, the feet being of sufficient length to engage against said parallel walls when said partition wall is twisted substantially out of right angular relation with said parallel walls, the right angularly extending feet being con-

nected to the partition wall by outwardly inclined legs.

8. A compartment forming structure for a refrigerator having a bottom panel and angularly arranged encircling wall panels secured marginally thereto, two of the wall panels being opposed and parallel, the structure including a partition wall of a length to fit between said parallel walls, right angularly extending feet at each end of said partition wall and designed to slidably support the partition wall upon the bottom panel of the refrigerator near the junctures thereof with said parallel wall panels, the feet being of sufficient length to engage against said parallel walls when said partition wall is twisted substantially out of right angular relation with said parallel walls, a second partition wall engageable with said first named partition wall to extend parallel to the parallel refrigerator walls, the second partition wall having hook means at one end engageable with the first partition wall for support thereby, and a leg at the other end resting upon the refrigerator bottom panel.

ENOCHE SWEDMAN.
